UNITED STATES PATENT OFFICE.

JULIUS A. HEINZ, OF PESOTUM, ILLINOIS.

BASE FOR CASKET EMBLEMS.

Application filed November 22, 1922. Serial No. 602,669.

To all whom it may concern:

Be it known that I, JULIUS A. HEINZ, a citizen of the United States, residing at Pesotum, in the county of Champaign and State of Illinois, have invented certain new and useful Improvements in Bases for Casket Emblems of which the following is a specification.

The present invention relates to a base for attachment to the lid of a burial casket and designed to support a crucifix or, in fact any emblematic device which it may be desired to mount upon the said lid. Ordinarily, caskets of the designs most commonly in use at the present time, have lids which are transversely rounded or bulged, and where an attempt is made to affix directly to such a lid a crucifix or other emblematic device, it is frequently found that this cannot be done successfully for the reason that some portions of the device will be spaced above the surface of the casket lid thus presenting an unsightly appearance. Therefore, the present invention has as its primary object to provide a base adapted to be applied to the lid of a casket and to conform to the curved contour of the lid, the upper surface of the base, however, being flat so as to provide a suitable supporting surface for the crucifix or other emblematic device.

In the accompanying drawings:

Figure 1 is a perspective view of one form of base embodying the invention applied to a casket lid of rounded contour and supporting a crucifix;

Figure 2 is a vertical transverse sectional view through the base and the crucifix supported thereon;

Figure 3 is a vertical longitudinal sectional view through the structure shown in Figure 2;

Figure 4 is a perspective view illustrating a modification of the invention.

The form of base illustrated in the drawings is designed essentially for the support of a crucifix and by its use undertakers are enabled to attach crucifixes of various sizes and designs to a casket lid regardless of the curved or bulged contour thereof. However, the invention is not restricted to a base of this particular design and intended for this particular use, inasmuch as other forms of bases may be provided for the sup-

port of the emblematic devices of fraternal orders, and the like.

In that form of the invention shown in Figures 1, 2 and 3 of the drawings, the base comprises a cruciform body which is formed of sheet metal and is of substantially hollow construction. In the drawings the casket lid is indicated in general by the numeral 1 and the base embodying the invention is indicated in general by the numeral 2, and comprises a standard portion 3 which corresponds to the standard of the cross of the crucifix indicated in general by the numeral 4, the crucifix comprising the usual body 5 representative of the cross and supporting the image 6. In addition to the standard 3, the base 2 comprises laterally extending branches or arms 7 which correspond to the arms or cross beam of the cross. In this embodiment of the invention both of these parts are formed from sheet metal and they may be integrally formed or formed separately and suitably united. For example, the standard 3 may comprise a top portion 8, depending side portions 9, and depending end portions 10. If the casket lid 1 is curved only from side to side, the lower edges of the sides 9 and ends 10 of the standard of the base may occupy a substantially common plane parallel to the top portion 8, as the curvature of the lid is, at its central portion, of no considerable degree. The arms 7 of the cruciform body of the base are of substantially the same construction as the standard and comprise a top portion 11, depending side portions 12, and depending ends 13. However, the lower edges of the sides 12 are of arcuate form as illustrated clearly in Figs. 2 and 3 of the drawings, to adapt them to snugly contact the transversely curved upper surface of the casket lid. In assembling the standard and the cross piece 7, the sides of the standard are cut away from their lower edges to the plane of the under side of the top portion 8, as indicated by the numeral 14, and the cross piece 7 is disposed within the recesses thus formed and is welded or otherwise permanently united to the standard 2. In order that the base, and the crucifix applied thereto and supported thereon, may be secured to the casket lid, the standard 2 of the base and the arms or cross piece 7 are formed in their top portions 8 and 11, respectively, with

openings 15 for the passage of securing elements such as nails or screws 16, these elements being also secured through the extremities of the cross 5 of the crucifix as shown in Figure 2.

It will be understood, of course, that the base may be made of any suitable metal, and if desired, enameled, or otherwise finished in keeping with the finish of the casket to which it is to be applied, and while the form above described is especially designed for attachment to metallic or metal sheathed caskets, it may be applied to caskets of wood or other material. However, where the casket is of wood it will no doubt be found desirable to make use of the modified structure shown in Figure 4, in which figure the base is indicated in general by the numeral 17 and is of wood and of solid construction, the under side of the base being transversely curved as indicated by the numeral 18 so as to conform to the curvature of the surface of the casket lid.

It will be understood that the principles of the invention may find embodiment in a crucifix per se, that is to say, the cross of

the crucifix might be made of the form of the base shown in either Figs. 2 and 3 or Fig. 4, and the image might be subsequently attached thereto or initially attached to or formed integrally thereon.

Having thus described the invention, what I claim as new is:

A support for a casket emblem having an outline corresponding to the outline of the emblem to be supported and consisting of intersecting members having flat tops and having depending elements at their sides and ends to rest directly on the top of a casket, the bottom surfaces of those depending elements which extend longitudinally of the support being rectilinear and the bottom surfaces of those elements which extend transversely of the support being concave to rest upon the arched top of the casket in contact therewith through their entire length, the support being further provided with openings to receive fastening elements whereby to secure an emblem to the support and the support to the top of the casket.

In testimony whereof I affix my signature.
JULIUS A. HEINZ. [L. S.]
